UNITED STATES PATENT OFFICE.

EDWARD LORING PRATT, OF NEWARK, NEW JERSEY, ASSIGNOR TO HENRY M. STRIEBY, OF SAME PLACE.

DESIGN FOR A CARRIAGE-STEP.

SPECIFICATION forming part of Design No. 19,584, dated January 14, 1890.

Application filed March 11, 1889. Serial No. 302,902. Term of patent 7 years.

To all whom it may concern:

Be it known that I, EDWARD LORING PRATT, a citizen of the United States, and a resident of the city of Newark, in the county of Essex 5 and State of New Jersey, have invented and produced a certain new and useful original Design to be forged, cut, or otherwise produced upon the article of manufacture called a Carriage-Step, of which the following is a specification, reference being had to the accompanying drawings, forming part of the same, in which—

Figure 1 is a face view of a carriage-step exhibiting my new design; and Fig. 2 is a 15 similar view, somewhat enlarged, of a piece of a carriage-step so ornamented.

This design consists, primarily, of a representation of a series of ribbon-like strips placed side by side and indented at regular 20 intervals, substantially as shown, together with solid and substantially perpendicular faces at the points where the indentations of one strip abut upon the adjoining strip, which design or pattern extends substantially 25 over the whole face of the step, but usually has a plain border at the edge.

This design has a partial resemblance to woven work, and also a resemblance to a number of cylindrical disks arranged upon edge and closely together in alternating regular 30 lines.

Projections *p* are sometimes formed upon the face of this design both for beauty and for use, which (as well as the disks) may extend in lines at right or any other angles to 35 the length of the step, or parallel therewith, the characteristic feature being the ribbon-like strips with faces, indentations, and sides, as shown, which feature is to appear upon the upper face of the step. 40

What I claim as my invention, and desire to secure by Letters Patent, is—

The design for a carriage-step, as herein shown and described.

Signed at Newark, in the county of Essex 45 and State of New Jersey, this 7th day of March, A. D. 1889.

EDWARD LORING PRATT.
